BRASSIÈRE

Gerald W. Gluckin, New York, N. Y., assignor to
 William Gluckin & Co., Inc., New York, N. Y.,
 a corporation of New York

Application July 17, 1948, Serial No. 39,222

2 Claims. (Cl. 2—42)

1

This invention relates to garments, generally identified as brassières. More particularly, the invention deals with garments of the type and kind, wherein the breast pockets, or the separate parts or sections from which the pockets are constructed, employ reinforcing stitchings for giving additional support and firmness to the resulting pockets. Still more particularly, the invention deals with devices of the character described, wherein the reinforcing stitchings are arranged parallel or substantially parallel to the vertical seams joining the sections of the pockets. The novel features of the invention will be best understood from the following description, when taken together with the accompanying drawing, in which certain embodiments of the invention are disclosed and, in which, the separate parts are designated by suitable reference characters in each of the views, and in which:

Fig. 1 is a front perspective view of a brassière made according to my invention; and

Fig. 2 is a detail view of one part of one cup, detached, illustrating the arrangement of reinforcing stitchings thereon.

In Fig. 1 of the drawing, I have shown a brassière comprising two similar pockets 10, 10'; each pocket being of the same construction, the brief description of one will apply to both. For example, the pocket 10 comprises four pocket-forming portions 11, 12, 13 and 14 and the pocket 10' comprises four pocket-forming portions 11', 12', 13' and 14'.

The various parts 11—14 are joined together by vertical seams 15—15' and horizontal seams 16—16'. Assemblage of these parts form the resulting pockets 10, 10' and these pockets are joined by a central substantially triangular portion 17, extending onto the lower edge portion of the pockets and joining side and back band portions 18, 18', the latter terminating at the rear end of the garment in a coupling hook or member 19 engaging suitable fastener means on a strap end 20. At 21, 21' are shoulder straps attached to the upper portions of the pockets 10, 10' and to the rear ends of the band portions 18, 18', as seen at 22, 22'.

In cutting the separate parts 11—14, 11'—14', the edges of these parts, which result in forming the horizontal seams 16, 16', for example, the edge 23 of the part 14 shown in Fig. 3, are formed curved; whereas the edge 24 of the part 14, seen in Fig. 2, and corresponding edges of the other parts, which result in forming the seams 15, 15', are formed straight.

All of the parts 11—14 have reinforcing stitch-

ings arranged thereon and these stitchings are

generally identified by the reference character 25 on the pocket 10 and 25' on the pocket 10'. These stitchings are arranged parallel, or substantially parallel, to the edge 24, so that, on the resulting pockets, all of these reinforcing stitches are disposed on the resulting pockets or the parts thereof vertically. Slight angularity of the stitchings would appear on the resulting extended pockets, as seen in Fig. 1, by virtue of the shape of the garment but actually, in each piece or part 11—14, 11'—14', the stitchings will be substantially parallel to the straight edges of the parts which form the resulting seams 15, 15'.

In garments of the type and kind under consideration, means in the form of reinforcing stitchings have been employed on the pockets or sectional portions of the pockets to give rigidity or stability thereto or in providing added support to the breast of the wearer. However, by providing stitches which are disposed vertically on the pockets or, in other words, extend in substantially vertical lines from the upper to the lower edges of the pockets, a firm support of the breast is

provided. In other words, a greater uplift is provided through the shoulder straps of the garment in the vertical straight line reinforcements, which are provided through the stitchings employed and, further, in the straight edges provided in the seams 15, 15'. Generally, in the construction of garments of the type and kind under consideration, it has been the practice to form the horizontal seams 16, 16' as straight seams or seams formed on straight edges of the pockets and the edges, forming the seams 15, 15', have been curved to give the required fullness to the pockets. In the present construction, this fullness is contributed to the garment by curving the edges 23 of the part 14 and correspondingly curving edges of the other parts which form the resulting seams 16, 16'.

It will be understood that, in producing the pocket structures of the garments of the type and kind under consideration, piece goods is stitched by parallel stitchings, as indicated, for example, in Fig. 2 and the patterns for cutting out the various parts of each pocket are so arranged on the piece goods as to have the straight edges 24 or corresponding edges of the associated parts arranged parallel to the stitchings after which the parts are stitched together in forming the seams 15, 15'; 16, 16'.

Having fully described my invention what I claim as new and desire to secure by Letters

2

1. A brassière of the class described comprising a pair of pockets, means joining the pockets and supporting the same upon the body of the wearer, each pocket being formed from a plurality of sections, joined by cross-seams, one seam being disposed horizontally and the other seam being disposed vertically on the pocket, the pocket sections at the vertical seams having straight edges, all sections of the pocket having parallel stitchings arranged over the area thereof, and said stitchings being substantially parallel to the vertical seams.

2. A brassière of the class described comprising a pair of pockets, means joining adjacent edges of the pockets, side and back bands having means at the rear portion of the garment for supporting the brassière about the body of the wearer, shoulder straps coupled with the pockets and the side and back bands for further support of the garment upon the body of the wearer, each pocket being formed from a plurality of pocket forming sections, the sections of each pocket being joined by vertical and horizontal seams,

all sections having straight edges at said vertical seams and curved edges at said horizontal seams, said sections having parallel stitchings through the area thereof, and said stitchings being substantially parallel to said straight edges of the sections.

GERALD W. GLUCKIN.
